United States Patent Office

Des. 175,839
Patented Oct. 18, 1955

175,839

NECKLACE OR THE LIKE

Adolph Katz, Providence, R. I., assignor to Coro, Inc.,
New York, N. Y., a corporation of New York

Application April 27, 1955, Serial No. 35,705

Term of patent 7 years

(Cl. D45—16)

Fig. 1

Fig. 2

FIG. 3

Fig. 1 is a plan view of a necklace or the like, showing my new design.

Fig. 2 is an edge view thereof.

Fig. 3 is an enlarged view of one of the links as shown in Fig. 1.

I claim:

The ornamental design for a necklace or the like, substantially as shown.
